CLAIM

The ornamental design for a shoe as shown and described.

DESCRIPTION

FIG. 1 is a rear bottom perspective view of a shoe showing my new design;

FIG. 2 is an opposite rear bottom perspective view thereof; and,

FIG. 3 is a bottom view thereof.

The unshaded regions inside of the eight quadrilateral shapes form no part of the claimed design. The broken lines immediately adjacent to the shaded area define the bounds of the claimed design and form no part thereof. The broken lines depicting the remainder of the shoe form no part of the claimed design.
